GRINDING MACHINE

William D. Schmidt, Worcester, Mass., assignor
to The Heald Machine Company, Worcester,
Mass., a corporation of Massachusetts

Application January 13, 1937, Serial No. 120,414

10 Claims. (Cl. 51—95)

The present invention relates to grinding machines and particularly to a machine in which the relative crossfeed movement between the wheel and workpiece may occur at a rapid rate 5 until the grinding wheel engages the workpiece.

In grinding machines operating upon cylindrical or tapered surfaces, the grinding wheel is normally given a crossfeed movement relative to the workpiece to bring the wheel and workpiece 10 into grinding contacts, and thereafter to procure successively deeper and deeper cuts in the workpiece until the latter reaches the desired finished size.

In internal grinding machines, it is essential 15 that the workpiece and the grinding wheel at the beginning of the grinding operation be positioned transversely of the machine relative to each other, so that the grinding wheel may enter the bore of the workpiece when either the wheel or 20 the workpiece is given an axial movement. The wheel is subsequently moved transversely to bring the grinding wheel and workpiece into grinding contact, and for reducing the inoperative time of each grinding operation, this cross- 25 feed movement must take place as rapidly as possible. One of the principal objects of the present invention is to provide for a rapid cross- feed movement with a provision for reducing the rate of crossfeed movement immediately upon 30 engagement between the wheel and workpiece independently of the unfinished size of the work- piece.

In a copending application filed by Schmidt and Blood, Serial No. 68,291, filed March 11, 1936, 35 is disclosed a structure by which the rate of cross- feed movement is reduced upon engagement between the wheel and the workpiece, and this structure incorporates a grinding wheel which is a conductor of electricity and forms part of a 40 circuit which is closed upon engagement between the wheel and the workpiece. This arrangement is entirely satisfactory in operation, but there are occasions when such an arrangement is not desir- 45 able, either by reason of the type of work- piece, the latter not being a conductor, or where the coolant forms such an insulation that a suit- able electrical contact between the wheel and workpiece cannot be effected. A further object 50 of the present invention is to provide for the reduction in the rate of crossfeed movement without the necessity for having a wheel or a workpiece which is an electrical conductor.

The present invention accordingly incorporates 55 an alternative mechanism for accomplishing the same result as in the Schmidt and Blood appli-

cation above referred to. In the present invention, the rate of crossfeed movement, or other change in the grinding operation, is procured in response to a slight lateral movement of the workhead on its supporting structure resulting 5 from engagement between the wheel and workpiece. Only a very small amount of lateral movement is necessary, and the arrangement is such that the change in the operation occurs immediately upon engagement of the workpiece by 10 the grinding wheel.

Other and further objects and advantages of the invention will more fully appear from the following detailed description, taken in connection with the accompanying drawings, in which— 15

Fig. 1 is a front elevation of a machine embodying the invention.

Fig. 2 is a plan view of the machine of Fig. 1.

Fig. 3 is a vertical section substantially along the line 3—3 of Fig. 2. 20

Fig. 4 is a vertical section substantially along the line 4—4 of Fig. 3, with parts broken away to show the crossfeed mechanism more clearly.

Fig. 5 is an end elevation partly in section of 25 a part of the crossfeed mechanism.

Fig. 6 is a fluid pressure diagram.

Fig. 7 is a wiring diagram.

Like reference characters refer to like parts in the different figures.

Referring first to Fig. 1, the machine has the 30 usual reciprocating table 1 provided in an internal grinding machine; either the grinding wheel or the workpiece to be ground is carried on said table, the reciprocations of the latter operating in either case to produce a relative translatory movement between the wheel and the workpiece. In the construction shown, the table supports and carries a work head 2 and the wheelhead 3, Figs. 2 and 5, is mounted on a bridge 4 which spans the guideways 5, Fig. 3, provided by the base 6 40 of the machine for the movements of the table 1. The grinding wheel 1 is carried on a spindle 8 journaled in the wheelhead 3, and is suitably rotated at a high rate of speed by any well known mechanism, which, in the present instance, consists of a motor, not shown, in the base of the machine, connected by a belt, also not shown, to a pulley 9 on the spindle. 45

The workpiece a, Figs. 1 and 2, is mounted in a suitable work-supporting structure which may 50 be in the form of a chuck 10 carried on a spindle 11 journaled in the workhead. The chuck is preferably driven at a relatively slow rate of speed from a motor 12 connected to the spindle 11 by a belt 13. The clutch mechanism 14, of 55

any well known construction, provides for stopping the rotation of the chuck without interference with the operation of the motor 12. The clutch mechanism is under the control of a handle 15 easily accessible to the operator of the machine.

The reciprocations of the table 1 to cause the desired relative traverse between the rotating grinding wheel and the work-supporting structure are imparted in any well known manner, as by the use of fluid pressure controlling and reversing mechanism, one type of which is described in the Blood and Burns Patent No. 2,011,705, dated August 20, 1935. It is sufficient 10 to note for the purpose of the present application that reversal of the table is procured at each end of the normal working stroke by spaced reversing dogs 16 and 17, which are carried by blocks 18 and 19 adjustably mounted on the front 20 of the table 1 and adapted alternately to engage and move a reversing lever 20. The reversing lever is connected by suitable mechanism to a reversing valve 21, Fig. 6. The reversing lever 20 during the grinding operation, when the grinding 25 wheel is within the bore of the workpiece, is so located as to be engaged alternately by the reversing dogs.

Referring now to Fig. 6, the pump 22, driven by a motor 23, directs fluid under pressure from 30 a tank 24 through a pipe 25 to a casing 26 in which the reversing valve 21 is positioned. The casing 26 has an inlet port 27 to which the pipe 25 is connected, and also has spaced outlet ports 28 and 29 connected by pipes 30 and 31, respectively, to the left and right hand ends of a cylinder 32 mounted in the base of the machine. A piston 33, slidable in the cylinder, has a piston rod 34 connected to a depending lug 35 on the table 1. The reversing valve alternately directs 40 fluid under pressure from the inlet port 27 to the outlet ports 28 and 29 and, at the same time, connects the opposite outlet port to an exhaust port 36 suitably connected to the tank.

The crossfeed movement between the workpiece and the grinding wheel is obtained by 45 transverse movement of the wheelhead 3 on the bridge 4. Movement of the cross-slide 37, Fig. 3, on which the wheelhead is mounted, is effected by rotation of the crossfeed screw 38, 50 which is held against endwise movement by anti-friction bearings 39 engageable with the rearward end thereof. The crossfeed screw engages an internally threaded portion 40 of the cross-slide for effecting the transverse movement 55 thereof. On the forward end of the crossfeed screw 38 is mounted a gear 41 which meshes with a pinion 42 secured against turning movement on a shaft 43 journaled in a housing 44 for the cross-feed mechanism. Also secured to the shaft 60 43 in spaced relation to the gear 42 is a ratchet wheel 45 engageable by spaced oppositely directed pawls 46 and 47, Fig. 4, carried by an annular member 48 secured against turning movement on a sleeve 49 journaled on the shaft 43. The 65 sleeve 49 has an integral pinion 50 engageable by a rack 51 horizontally slidable in the casing 44, said rack being held in engagement with the pinion by a bearing 52. The rack 51 is shifted by a fluid pressure mechanism, hereinafter 70 described in detail, and procures through the pawl and ratchet arrangement a rotation of the shaft 43, and accordingly a rotation of the crossfeed screw. Manual rotation of the crossfeed screw is by a hand wheel 43' on the end of the shaft 43. 75 The pawl and ratchet arrangement is fully

described in the Guild Patent No. 1,971,138, dated August 21, 1934. It is sufficient to note for the purpose of the present application that this double pawl arrangement permits, during the return of the crossfeed slide to original position 5 in readiness for a subsequent grinding operation, a compensation for the reduction in size of the grinding wheel as a result of wear and the dressing operation performed thereon during the preceding grinding operation. With reference again 10 to Figs. 3 and 4, it will be noted that both of the pawls are normally held in operative engagement with the ratchet by a spring 53, so that a rotation of the annular member 48 provides a corresponding rotation of the ratchet 45. The pawl 15 47 is operative during the crossfeed movement, and the pawl 46 is operative during the retraction of the crossfeed movement, the latter involving a counterclockwise rotation of the member 48. The pawl 46 is rendered inoperative 20 during a part of the movement of the annular member 48 in the counterclockwise direction, so that the cross-slide is retracted a slightly shorter distance than it is moved during the crossfeed movement.

To effect this compensatory movement, the shaft 43 has journalled thereon an arm 54 having a gear segment 55 on the outer end thereof. The gear segment engages with a pinion 56 on a shaft 57 journalled in the front wall of the housing 44. The outer end of the shaft 57 has a knurled knob 58 by which said shaft is turned for shifting the position of the arm 54. Integral with the arm 54 is a cam 59 in a position for engagement with a pin 60 on the pawl 46 just 35 before the termination of the crossfeed movement. Thus during the first part of the retraction of the crossfeed movement, the pawl 46 is inoperative and a rotation of the annular member 48 procures no corresponding movement of the ratchet wheel until the pawl 46 is released by the cam 59. During the remainder of the counterclockwise movement of the member 48, the retraction of the crossfeed movement takes place.

Referring now to Figs. 4 and 6, the rack 51 is carried on the end of a piston rod 61, extending from a piston 62 slidable in a horizontally positioned cylinder 63 mounted on the front of the bridge. Fluid under pressure is directed 50 alternately to opposite ends of the cylinder 63, for procuring a crossfeed movement and the retraction thereof. As shown in Fig. 6, fluid under pressure from the pipe 25 passes through a pipe 64 to the inlet port 65 of a reversing valve casing 66 for a reversing valve 67 for the crossfeed mechanism. An outlet port 68 in the casing is connected by a pipe 69 to the left hand end of the cylinder 63, and a port 70 is connected by a pipe 71 and suitable valve mechanisms, hereinafter 60 described, to the right hand end of the cylinder. An exhaust port 72 for the reversing valve casing provides for exhaust of fluid from the end of the cylinder, and this port is suitably connected to the tank 24.

The admission of fluid to the right hand end of the cylinder 63 from the valve 67 is controlled by a horizontally slidable valve 73 positioned in a casing 74 forming part of a housing 75, Fig. 5, mounted in front of the wheelhead. The pipe 70 75 is connected to a port 76 in the casing 74 and fluid connection is normally provided between this port and an outlet port 77 by a reduced portion 78 of the valve. The port 77 is connected by a conduit 79 to the right hand end of the 75

cylinder 63. Fluid under pressure thus enters the cylinder 63 for a crossfeed movement at a maximum rate.

When the grinding wheel engages the workpiece the valve 73 is automatically shifted, by mechanism hereinafter described, for cutting off the flow of fluid through this valve. The crossfeed movement is then under the control of a valve 80, Figs. 4 and 6, positioned in a casing 81 in a block 82 mounted on the front of the bridge above the cylinder 63. The pipe 11 is connected by a branch conduit 83 to a channel 84 in the block 82, this channel intersecting spaced bores in the block in which a rough feed valve 85 and a fine feed valve 86 are respectively positioned. The casing 81 has a port 87 communicating with the valve 85 and a port 88 communicating with the valve 86.

The valve 80 is normally in the position shown, 20 with a reduced portion 89 of said valve providing fluid connection between the port 85 and a channel 90 in the casing 81 and block 82, this channel communicating with a channel 91 to the right hand end of the cylinder 63. Thus when 25 fluid flowing through the valve 73 is cut off, the crossfeed movement continues at a reduced rate as determined by the setting of the rough feed valve 85.

During the grinding operation, and subsequent 30 to the shifting of the valve 73, the valve 80 is automatically shifted by mechanism hereinafter described, thereby cutting off the port 87, and establishing fluid connection from the port 88, around a reduced portion 92 of the valve to a 35 channel 93 intersecting the channel 90. The rate of crossfeed movement is thus further reduced and continues at an extremely slow rate as determined by the fine feed valve 86.

With reference to Fig. 4, the valve 80 is normally held in the position shown by a coil spring 94 at the right hand end of the valve. Movement of the valve to the left beyond the position shown is limited by a plunger 95 engageable with the left hand end of the valve and positioned 45 in a projecting lug 96 on the cylinder 63. A cap 97 on the lug limits movement of the plunger to the left. During the grinding operation a cam 98 on the member 48 engages a roller 99 on the plunger 95, thereby shifting the valve 80 50 to the right as above pointed out.

The structure above described is similar to structure already described and claimed in prior patents and pending applications and is not, of itself, the present invention. The latter involves, in connection with the above or similar grinding machine elements, the attainment of the objects and novel features above set forth. In accordance with the present invention, the movement of the wheelhead relative to its supporting structure, resulting from engagement between the wheel and a workpiece procures a change in the grinding operation, which, in the present embodiment of the invention, is a reduction in the rate of crossfeed movement.

65 Referring to Fig. 5, the wheelhead 3 is mounted for a slight oscillation relative to the supporting structure, and, is accordingly supported on a slide 100, which is secured in turn to the cross-slide 37, by one or more flat springs 101. The latter are secured to a lug 102 on the slide 70 and form a cantilever support for the wheelhead to which the upwardly extending ends of the springs are secured. A projecting lug 103 on the wheelhead is normally slightly spaced 75 from the slide 100 and is moved into engage-

ment therewith by contact between the wheel and the workpiece.

When the wheelhead is rocked counterclockwise, a solenoid 104 is energized, as later described, to rock an arm 105 journalled in a lug 106 on the housing 15. The arm 105 has a cam 107 at its lower end, engaging with the lug 103, and the wheelhead is thus locked against rocking movement by energization of the solenoid 104. The armature 108 of the solenoid, 10 which is connected to the arm 105, is also integral with the valve 73 for movement of the latter when the solenoid is energized.

The wheelhead 3 has a projecting rod 109 having its free end located between two coils 110 and 111 on a bracket 112 secured to the slide 100, by which the energization of the solenoid 104 is procured. A hood 113 extends over the wheelhead 3 and associated mechanism and has a heating coil 114 therein for maintaining 20 a constant temperature therein, so that the actuating mechanism will function uniformly. A thermometer 115 may be positioned in the hood 113, if desired.

With reference to Fig. 7, a source of alternating current is represented by the parallel leads 116 and 117 to which the heating coil 114 is connected by leads 118 and 119. In the lead 118 is positioned a thermostatically controlled switch 120 for maintaining a constant temperature under the hood.

The primary winding 121 of a transformer is connected to the leads 116 and 117, and one terminal of the secondary winding 122 is connected to the opposed coils 110 and 111 by a 40 lead 123. The opposite terminal of the secondary winding 122 is connected by a lead 124 to one terminal of each of a pair of opposed coils 125 and 126 oppositely wound on a magnetic core 127. The opposite terminals of these coils 45 125 and 126 are connected to the terminals of the coils 110 and 111 by leads 128 and 129. The two coils 110 and 111 form two arms of a Wheatstone bridge and the other two arms are the coils 125 and 126 with the rod 109, which forms 45 an armature located midway between the coils 110 and 111, no voltage will be induced in a secondary winding 130 on the core 127.

The winding 130 is connected by leads 131 and 132 to opposite terminals of a suitable bridge rectifier 133 of familiar construction. The other terminals of this rectifier are connected by leads 134 and 135 to the coil 136 of a suitable micro-ammeter 137. The indicating needle 138 of this micro-ammeter is in a position to engage the 55 conducting fluid 139 in a cup 140. A source of direct current is represented by the parallel leads 141 and 142, one of which is connected to the needle 138 and the other connected to the solenoid 104. The opposite terminal of the solenoid is connected by a lead 143 to the cup 140. When the Wheatstone bridge becomes unbalanced by rocking of the wheelhead, thereby shifting the position of the rod 109 relative to the coils 110 and 111, the micro-ammeter will 65 be energized, thereby rocking the needle 138 for closing the circuit through the solenoid 104.

In the operation of the machine, a workpiece having been positioned in the workhead and the latter having been set in rotation, the wheel and work are brought into operative relation by shifting the reversing valve 21 from the position shown, this valve movement being effected by a lever 144 on the front of the machine, the lever being suitably connected to the reversing 70 75

valve. As the table moves into operative position the valve 67 is shifted from the position shown by any suitable mechanism, not shown, but preferably in response to the table movement, for procuring the crossfeed movement.

The valve 73 being in the position shown, the crossfeed movement occurs at the maximum rate, moving the wheel laterally from the position shown in Fig. 3, into engagement with the workpiece bores. When engagement between the workpiece and grinding wheel takes place, the wheelhead is rocked counterclockwise, Fig. 5, thereby procuring energization of the solenoid 104 for locking the wheelhead against further rocking movement and for shifting the valve 73 to reduce the rate of crossfeed movement. The solenoid continues to be energized during the remainder of the grinding operation.

When the workpiece is ground to the desired size the grinding operation is terminated by any suitable mechanism, which may be the controlling mechanism of the Blood and Burns Patent No. 2,011,075, above cited. In any event, the grinding operation is brought to a close by an extended movement of the table 1 to the left into the rest position shown. During the extended movement, a cam 145, Fig. 1, on the table, engages the projecting arm 146 of a switch 147 positioned in the lead 132 to break the circuit through the solenoid 104 in readiness for a subsequent grinding operation. When the solenoid is de-energized the wheelhead returns to the position shown, thereby restoring the position of the rod 109 to again balance the Wheatstone bridge.

During the extended movement of the table the valve 67 is also shifted into the position shown for a retraction of the crossfeed movement. When the solenoid 104 is de-energized, the valve 73 is restored to original position allowing exhaust of fluid through this valve from the cylinder 63.

From the foregoing it will be apparent that the present invention provides a mechanism by which a change in the grinding operation is effected upon engagement between the grinding wheel and the workpiece by the arrangement shown, the change involving a reduction in the rate of crossfeed movement procured by a movement of the wheelhead relative to the machine. By this arrangement the wheel may be moved laterally of the workpiece at a maximum rate until it comes in contact with the workpiece.

I claim:

1. In a grinding machine, a wheel supporting member having a wheel thereon, a work-supporting member having a workpiece mounted therein, means for procuring a relative movement between said members, means responsive to engagement between the wheel and the workpiece for procuring a movement of one of said members relative to the supporting structure therefor, and means responsive to said last movement for locking the movable member against further movement relative to the supporting structure, said last means including a cam.

2. In a grinding machine, a wheel supporting member having a wheel thereon, a work-supporting member having a workpiece mounted therein, means for procuring a relative movement between said members, means responsive to engagement between the wheel and the workpiece for procuring a movement of one of said members relative to the supporting structure therefor, and means responsive to said last move-

ment for locking the movable member against further movement relative to the supporting structure, said last means including a cam and a solenoid for actuating said cam.

3. In a grinding machine, a wheel supporting member having a wheel thereon, a work-supporting member having a workpiece mounted therein, means for procuring a relative movement between said members, means responsive to engagement between the wheel and the workpiece for procuring a movement of one of said members relative to the supporting structure therefor, and means responsive to said last movement for locking the movable member against further movement relative to the supporting structure, said last means including a cam and a solenoid for actuating said cam, said solenoid being energized in response to said last movement.

4. In a grinding machine, a wheel supporting member having a wheel thereon, a work-supporting member having a workpiece mounted therein, means for procuring a relative movement between said members, means responsive to engagement between the wheel and the workpiece for procuring a movement of one of said members relative to the supporting structure therefor, means responsive to said last movement for procuring a change in the rate of relative movement between the members, and cam means simultaneously operative for locking the movable member against further movement relative to the supporting structure.

5. In a grinding machine, a wheel supporting member having a wheel thereon, a work-supporting member having a workpiece mounted therein, means for procuring a relative movement between said members, means responsive to engagement between the wheel and the workpiece for procuring a movement of one of said members relative to the supporting structure therefor, means responsive to said last movement for procuring a change in the rate of relative movement between the members, cam means simultaneously operative for locking the movable member against further movement relative to the supporting structure, and a solenoid for shifting said cam, said solenoid being actuated in response to said last movement.

6. In a grinding machine, a wheel supporting member having a wheel thereon, a work-supporting member having a workpiece mounted therein, hydraulically actuated means for procuring a relative movement between said members, means responsive to engagement between the wheel and the workpiece for procuring a movement of one of said members relative to the supporting structure therefor, valve means for controlling the hydraulically actuated means, cam means for locking the movable member against movement relative to the supporting structure, and a solenoid for actuating the cam and valve, said solenoid being energized in response to the movement of the movable member relative to the supporting structure.

7. In a grinding machine, a wheel head having a wheel spindle journalled thereon for supporting a grinding wheel, a workhead having a workpiece mounted therein, means for procuring a relative movement between said heads, means responsive to engagement between the wheel and the workpiece for procuring a shifting movement of one of said heads relative to the supporting structure therefor, means for procuring a change in the rate of relative movement between the

heads, a solenoid for actuating said last means, and means for energizing the solenoid, said means including a normally balanced circuit and means for unbalancing the circuit to energize the solenoid in response to said shifting movement.

8. In a grinding machine, a wheel head having a wheel spindle journaled thereon for supporting a grinding wheel, a workhead having a workpiece mounted therein, and means for procuring a relative movement between said heads to bring the wheel and workpiece into engagement, means for supporting one of the heads for shifting movement relative to its supporting structure in response to engagement between the wheel and workpiece, an armature carried by the shiftable head for shifting movement, a coil carried by the supporting structure relative to which the armature is movable, a circuit including said coil, a solenoid adapted to be energized by a change in the circuit resulting from movement of the armature relative to the coil, and means controlled by said solenoid for procuring a change in the relative movement between the heads.

9. In a grinding machine, a wheel head having a wheel spindle journaled thereon for supporting a grinding wheel, a workhead having a workpiece mounted therein, hydraulically actuated means for procuring a relative movement between said heads to bring the wheel and workpiece into engagement, means for supporting one of the heads for shifting movement relative to its supporting structure in response to engagement between the wheel and workpiece, an armature carried by the shiftable head for shifting movement, a coil carried by the supporting structure relative to which the armature is movable, a circuit including said coil, a solenoid adapted to be energized by a change in the circuit resulting from movement of the armature relative to the coil, and means controlled by said solenoid for procuring a change in the relative movement between the heads.

ture carried by the shiftable head for shifting movement, a coil carried by the supporting structure relative to which the armature is movable, a circuit including said coil, a solenoid adapted to be energized by a change in the circuit resulting from movement of the armature relative to the coil, and a valve controlled by said solenoid for procuring a change in the relative movement between the heads.

10. In a grinding machine, a wheel supporting member having a wheel thereon, a work-supporting member having a workpiece mounted therein, hydraulically actuated means for procuring a relative movement between said members to bring the wheel and workpiece into engagement, means for supporting one of the members for shifting movement relative to its supporting structure in response to engagement between the wheel and workpiece, an armature carried by the member for shifting movement, a coil carried by the supporting structure relative to which the armature is movable, a circuit including said coil, a solenoid adapted to be energized by a change in the circuit resulting from movement of the armature relative to the coil, a valve controlled by said solenoid for procuring a change in the relative movement between the members, and cam means also under the control of said solenoid for locking the shiftable member against further movement relative to the supporting structure. 30

WILLIAM D. SCHMIDT.
